UNITED STATES PATENT OFFICE.

CHARLES B. BOSWORTH, OF SOMERVILLE, MASSACHUSETTS, ASSIGNOR TO
STAR BRASS MANUFACTURING COMPANY, OF BOSTON, MASSACHUSETTS,
A CORPORATION OF MASSACHUSETTS.

STEAM-ENGINE INDICATOR.

SPECIFICATION forming part of Letters Patent No. 687,391, dated November 26, 1901.

Application filed March 15, 1901. Serial No. 51,227. (No model.)

To all whom it may concern:

Be it known that I, CHARLES B. BOSWORTH, a citizen of the United States, residing at Somerville, in the county of Middlesex and State 5 of Massachusetts, have invented a new and useful Improvement in Steam-Engine Indicators, of which the following is a full, clear, and exact description, reference being had to the accompanying drawings, forming a part of 10 this specification, in explaining its nature.

The invention relates to a steam-engine indicator having a base or support provided with an integral cylinder-holder and to the form of cylinder combined therewith.

15 It further relates to means for the adjustment of the pencil from without the cylinder and to details of construction which will hereinafter be described.

Referring to the drawings, Figure 1 is a 20 view of a steam-engine indicator having some of the features of my invention part in elevation and part in section. Fig. 2 is a detail view, enlarged, of an adjustable swiveling connection between the piston-rod and the pencil-lever. Fig. 3 is a view illustrating a gearing-down or reducing mechanism. Fig. 4 is a plan thereof inverted. Figs. 5 and 6 represent a paper-drum clutch, to which reference is hereinafter made.

30 In the drawings, A is the plate of the indicator. It has at one end, extending principally from its under or back side, an integral cylindrical casing a, which has at its lower end a coupling a' and at its upper end a seat a². It forms a continuous chamber a³, open at both ends and cylindrical in shape. It has in its interior adjacent to the seat a² the annular channel a⁴, which is connected at one side with the outer air by the diagonal holes 35 or passages a⁵, which extend from the channel diagonally through the casing. (See Fig. 1.) Adjacent to the annular channel is the interior screw-threaded section a⁶.

B is the cylinder, in which the piston b 45 moves and which also serves to hold the cap b', which furnishes the guide for the piston-rod b². The cylinder is of a length to extend into the chamber a³ of the casing a almost its entire length and to also extend from the cas-

ing on the upper side of the plate A to any 50 desired extent. It is provided with the screw-threaded section b³, which engages the threaded section a⁶ of the casing a, the seat b⁴, which comes in contact with the seat a² of the casing when the cylinder has been fully screwed 55 to place in the casing, the holes b⁵, which connect its interior chamber b⁶ above the piston with the annular channel a⁴, the threaded section b⁷ at its outer end, with which the threaded portion b⁸ of the cap b' engages, and 60 it is further shaped with respect to the casing a to provide the long narrow jacket-forming chamber b⁹ between it and the casing a and which is constantly connected with the source 65 of steam-supply or power.

A sleeve C surrounds the uncovered portion of the cylinder on the upper side of the plate and furnishes supports for the link-ear c and the link-post c'. It is held against the shoulder of the cylinder which forms the seat 70 b⁴ by an extension of the cap b'.

The pencil-lever D is pivoted at d to the link d', which is itself pivoted to an ear c, fast to the sleeve C. The pencil-lever is also pivoted at d² upon a link d³, which itself is pivoted to the upper end of the post c', mounted upon an extension from said sleeve C. The pencil-lever is connected to the piston-rod d² outside the cylinder and above the cap b' by a link d⁴, which is pivotally connected to the 80 pencil-lever between its pivotal points d and d² and upon the line of movement of the piston-rod, and also to the upper end of a coupling d⁵, which connects the link d⁴ with the end of the piston, and which coupling not 85 only forms a swivel-jointed connection between the link d⁴ and the piston-rod, but also means whereby the distance between the link d⁴ and the piston-rod may be varied or adjusted at will upon the outside of the cylinder and without the removal of any part of the indicator and for the purpose of permitting the adjustment of the position of the pencil d⁶ at the outer end of the pencil-lever D along the side of the drum D', upon which 90 the indicator-card is mounted. The piston-rod is provided with a long threaded hole d⁷, extending from its outer end. The coupling

d^5 has a long threaded stem d^9 to enter the threaded hole in the piston-rod. Its outer end is enlarged and provided with a hole d^{10} , an exterior screw-thread d^{11} , and a seat d^{12} . 5 A cap d^{13} , having a recess d^{14} , screws onto the enlargement and serves to secure to it a member d^{15} of a swivel-joint, which comprises a pivot d^{16} to fit the hole d^{10} and a collar d^{17} to extend into the recess of the cap between 10 it and the seat d^{12} . The upper end of this joint member d^{15} is provided with ears, between which the pencil-lever link d^4 is pivoted. The swivel connection is above and beyond the upper end of the cylinder, and a 15 portion of it forms the end of the adjusting device or connection with the piston-rod, and thereby provides means by which the adjusting device may be actuated by hand outside the cylinder without requiring the removal 20 in any way of any part of the indicator, thus permitting the adjustment of the pencil to be instantly made at will without varying any other relation between it and the piston-rod.

In Fig. 1 the drum is represented as not 25 geared down. In Fig. 5 it is shown as provided with a clutch which is engageable at will with the cord-spool f . It comprises the holder f' , having a recess f^2 toward the spool f of a size to receive a clutch-ball F and 30 permit it to move tangentially with respect to the surface of the spool. A spring f^3 bears against the ball and keeps it in contact with a controller f^4 . This controller is in the shape of a plate which is movable toward and 35 from the holder f' by screwing or unscrewing the stud or handle f^5 . The partial unscrewing of the handle permits the controller to be moved away from the holder sufficiently to allow the ball to engage with the spool and 40 then act as a clutch in preventing the spool from turning backward. It is of course free to be moved in the reverse direction. By turning the handle in the reverse direction and moving the controller against the holder 45 the ball is removable from the spool to an inactive position and the spool is no longer engaged by a clutch. The side f^6 of the recess f^2 may be slightly inclined away from the periphery of the spool, as represented in 50 Fig. 5. This makes the engagement and disengagement of the ball obtainable in a very short movement of it in one direction or the other.

In Fig. 3 I have shown the drum as geared 55 down by mechanism comprising the gear G at the base of the drum, the pinion g , to mesh with it, mounted upon the upper end of the shaft g' , and the cord-spool g^2 , fastened to the shaft g' . The shaft is supported by the 60 bracket g^3 , attachable to and detachable from the plate A by a drum-clamping screw g^4 .

It will be seen that the construction of cylinder shown and described provides for a perfect alinement of the piston and piston-rod 65 bearing, as the piston-rod bearing is attached directly to an integral extension of the cylinder, so that the piston-rod bearing is directly

connected with the cylinder. This construction is of value in the manufacture of this part of the instrument and also in the subsequent use and wear of it. The way in which the cylinder and piston-rod bearing are mounted upon the plate is also of importance, because of the simplicity and firmness or rigidity of the support and also because of 70 the nature of the exhaust-channel and its connections with the outer air and the manner in which the steam-jacket about the cylinder is provided, the whole being obtained by a direct application of correct principles 75 of construction which cheapen the construction, improve the operation, and lengthen the operation of the indicator.

Having thus fully described my invention, I claim and desire to secure by Letters Patent 80 of the United States—

1. In a steam-engine indicator, the combination of a supporting-plate provided with an integral cylinder-holder extending mainly from the lower side of the plate and having 90 an open end surrounded by a seat and an interior threaded section adjacent to the seat, with a cylinder, a portion of which is contained in said holder and a portion of which extends from it, which cylinder has a shoulder to bear against the seat, an interior threaded section to engage the threaded section of the holder, and an extension from the threaded section in the holder sufficiently less in size than the bore of the part of the holder 100 against it to form a continuous chamber surrounding the cylinder and connected with the chamber of the holder below the cylinder thereby forming an extension of said chamber about the cylinder adapted to receive and 105 contain a live-steam jacket for the cylinder.

2. In a steam-engine, the combination of the base-plate, an integral cylinder-holder extending from said base-plate, having an open end surrounded by a seat, an annular 110 channel adjacent to said seat opening to the outer air, and a threaded section adjacent to the annular channel, with a cylinder having a portion contained in the said cylinder-holder, provided with a shoulder to bear 115 against the seat, perforations against said annular channel and opening into it through which spent steam may escape, a threaded section to engage the threaded part of the holder, and an extension of the cylinder into 120 the holder from said threaded end supported entirely from said threaded section and providing between it and the holder an unobstructed chamber connecting with the steam-chamber of the holder for holding a live-steam 125 jacket about the cylinder, not connected with or opening into the outer air.

3. In a steam-engine indicator, the combination of a base-plate provided with an integral cylinder-holder having an opening at 130 one end, a seat surrounding said opening, an annular channel opening into the outer air, a threaded section adjacent to said annular channel, and a live-steam chamber, a one-piece

cylinder, a portion of which is contained in the holder and a portion of which extends from the holder and serves as a support for the piston-rod and pencil-lever arms, the said 5 cylinder also having a shoulder to bear against said seat, a perforated section against said channel through which spent steam may escape, a threaded section to engage the threaded section of the holder, and an extension into 10 the live-steam chamber of the holder separated from the wall of the holder by an annular chamber connected only with the live-steam chamber, and the piston, piston-rod, pencil-lever connected with the piston-rod, and the 15 paper drum.

4. In a steam-engine indicator, the combination of a plate provided with an integral cylinder-holder upon one side, a cylinder and a piston-rod-bearing support, a portion of 20 which is contained within said holder and is attached thereto by interior threaded connections and an exterior shoulder and seat, and a portion of which projects from said cylinder-holder and furnishes a support for a piston-rod bearing and for the sleeve of a post-holding bracket, said piston-rod bearing, said sleeved post-holding bracket, a piston, a piston-rod, a pencil-lever, and means for connecting it with said piston-rod, said means 25 consisting of a threaded stem adjustably attached to the piston-rod and the outer end of which forms one member of a coupling, another member of the coupling adapted to turn in said stem-coupling and a link hinged 30 to said turning coupling and to said pencil-lever as described.

5. In a steam-engine indicator comprising a piston and a cylinder, a piston-rod and a pencil-lever, an adjustable means connecting 35 said pencil-lever with said piston-rod comprising a threaded stem adjustably mounted

on the piston-rod and formed at its outer end outside the cylinder-cap to provide a member of a coupling, a coöperating member of the coupling adapted to turn in the said first- 45 named member and a link connecting said coöperating member of the coupling with said pencil-lever and whereby upon turning the stem member of the coupling the distance between said pencil-lever and said piston may 50 be varied from outside of the said cylinder without disturbing said piston, as and for the purposes set forth.

6. The combination in a steam-engine indicator of the drum-spool and a clutch mounted upon the plate A and adjustable thereon to an operative or an inoperative position. 55

7. The combination in a steam-engine indicator of the drum-spool, the plate upon which it is mounted, a clutch carried upon said 60 plate, comprising a holder fixed to the plate, having a tangential recess adjacent to the periphery of the spool, a roll or ball movable lengthwise said recess, a spring for moving it in one direction and an adjustable controller for limiting the extent of its movement, whereby it may be allowed to take an operative position or may be restrained from operation. 65

8. The combination in a steam-engine indicator, of a drum having a gear mounted upon its lower end of substantially equal diameter therewith, a bracket attached to the drum-plate carrying a shaft having a pinion at its upper end to engage said gear and also 70 carrying a cord-drum of greater diameter than said pinion, as and for the purposes described. 75
